(57) **CLAIM**

What is claimed is the ornamental design for a squat rack, as shown and described.

DESCRIPTION

FIG. 1 is a front perspective view of an embodiment of the new squat rack of Applicant's invention.

FIG. 2 is a front view thereof.

FIG. 3 is a rear view thereof.

FIG. 4 is a side view thereof.

FIG. 5 is a side view thereof.

FIG. 6 is a top view thereof.

FIG. 7 is a bottom view thereof.

FIG. 8 is a front perspective view of a second embodiment of the squat rack with a barbell holder.

FIG. 9 is a front perspective view of a third embodiment of the squat rack.

FIG. 10 is a front view of the third embodiment of the squat rack.

FIG. 11 is a rear view of the third embodiment of the squat rack.

FIG. 12 is a side view of the third embodiment of the squat rack.

FIG. 13 is a side view of the third embodiment of the squat rack.

FIG. 14 is a top view of the third embodiment of the squat rack; and,

FIG. 15 is a bottom view of the third embodiment of the squat rack.

The broken lines in the figures are used to represent subject matter that forms no part of the claimed design.
